United States Patent Office.

MARK W. HOUSE, OF CLEVELAND, OHIO.

Letters Patent No. 76,764, dated April 14, 1868.

IMPROVEMENT IN LAMPS.

The Schedule referred to in these Letters Patent and making part of the same.

TO ALL WHOM IT MAY CONCERN:

Be it known that I, MARK W. HOUSE, of Cleveland, county of Cuyahoga, in the State of Ohio, have invented a new and improved Lamp; and I do hereby declare that the following is a full and exact description thereof, reference being had to the accompanying drawings, and to the letters of reference marked thereon.

Figure 1 is a half section, representing my new adapter and tube in their relation to the lamp and burner.

The nature of my invention consists in placing an adapter, B, between the burner, A, of a common kerosene-lamp and the collar, C, or body of the lamp, made to receive the burner. The adapter B may be made of any suitable non-conducting or poor conducting material, such as wood, glass, rubber, &c. The object gained in using the adapter B is to insulate the burner A from the body of the lamp, and thereby prevent the heat generated by the burner A descending to the body of the lamp, and raising the temperature of the oil which it may contain.

Attached to the lower end of the adapter B is a tube, D, into which a second tube, E, is fitted, both sliding together, having a telescopic adjustment, by which they can be lengthened or shortened, to correspond to the depth of the reservoir of a lamp containing oil. As a matter of convenience in adjusting the sliding tubes D & E to the lamp, the lower end of the tube E is made serrated, to allow the points to rest on the bottom of the oil-reservoir. Near the upper end of the oil-reservoir C, I make minutely fine holes, e e, through the tube D or lower part of the adapter B. These small holes e e (size of No. 26 American wire gauze is found to answer the purpose very well) are designed to allow a free escape of any gases that might be generated in the reservoir C, outside of the tube D, to pass into it, and up the wick-tube into the flame.

It will be seen that the wick is to be held inside the tube D, and the oil supplied to it at the bottom through the serrated openings e e, in the direction of the red arrows, which are always in contact with the heaviest or less volatile oil.

Another object sought to be gained by the application of the tube D is safety in refilling the lamp with oil. The burner is detached from adapter B, and the oil poured into the tube D, passing under the serrated end of the tube E, and rising in the reservoir outside of the tubes D and E, expelling the air through the minute openings e into the tube. Should a flame be communicated to the lamp while it is being filled, it will be confined to the tube alone, as it could neither pass through the solid oil at the bottom, nor through the minute openings at the top of the reservoir.

Any convenient way of securing this tube in the reservoir, or making it a stationary part of the lamp, would produce the same effect as to have it movable or attached to the adapter.

What I claim as my invention, and desire to secure by Letters Patent, is—

The adapter B, in combination with the tube D & E, substantially as arranged and described, for the purpose set forth.

MARK W. HOUSE.
